UNITED STATES PATENT OFFICE.

GEORGE D. WILKINSON AND AUGUSTUS F. HARTER, OF OAK PARK, ILLINOIS, AS
SIGNORS TO CRIBBEN & SEXTON COMPANY, OF CHICAGO, ILLINOIS, A CORPORATION
OF ILLINOIS.

OVEN DOOR.

Application filed November 16, 1923. Serial No. 675,413.

To all whom it may concern:

Be it known that we, GEORGE D. WILKINSON and AUGUSTUS F. HARTER, citizens of the United States, residing at Oak Park, in the county of Cook and State of Illinois, have invented new and useful Improvements in Oven Doors, of which the following is a specification.

This invention relates particularly to oven doors; and the primary object is to provide an improved construction involving the use of an outer sheet metal panel constituting the main body of the door, an inner sheet metal lining, and a pair of trunnions having reinforcing shanks housed between the main panel and the lining. Such a construction provides for the supporting of the door and any load which may be imposed upon it when the door is in open condition by the trunnions and the shank-extension thereof, which suitably may be made of cast iron and of sufficient strength to readily support the door and any superimposed weight which may be imposed upon it in use.

The invention is illustrated in its preferred embodiment in the accompanying drawings, in which—

Fig. 1 represents a broken elevational view of a gas range equipped with the improved door; Fig. 2, a horizontal sectional view taken as indicated at line 2 of Fig. 1, but showing the door in open position and a portion of the lining of the door broken away; Fig. 3, a broken vertical section taken as indicated at line 3 of Fig. 2; Fig. 4, a broken section showing one of the journals or trunnions and its bearing; Fig. 5, a broken perspective view showing one corner of the lining member of the door; Fig. 6, a broken perspective view showing one corner portion of the main panel of the door; Fig. 7, a broken vertical sectional view illustrating an improved latch for the door, the section being taken as indicated at line 7 of Fig. 1; Fig. 8, a plan view of a door, illustrating a modification, the lining being removed; Fig. 9, a broken perspective view illustrating another modification in which the trunnions which support the door are of another form; and Fig. 10, a broken vertical sectional view taken as indicated at line 10 of Fig. 9.

Referring to Figs. 1 to 7 inclusive, A represents the frame of a range which is provided with ovens equipped with doors A'

and A². In this embodiment of the invention, the frame A is equipped with bearings, or journal boxes B for the trunnions of the doors. The members B are provided with stops 1 which are adapted to limit the downward swing of the door. The doors A' and A² are of the same construction and mounted in the same manner. A description of one will suffice.

The door A' comprises a main outer sheet metal panel 2 which is bowed outwardly and is provided at its periphery with end flanges 2^a, a lower flange 2^b, and an upper flange 2^c; an inner sheet metal panel 3, which is provided at its margins with end flanges 3^a, a lower flange 3^b, and an upper flange 3^c; trunnions 4 received by the bearings B and equipped with shanks 4^a which are housed in the space between the outer and inner panels 2 and 3; a handle 5 secured to the upper portion of the door; and a latch 6 carried by the frame A and adapted to engage the upper edge of the door when the door is in the closed position.

The flanges of the main panel 2 of the door are notched at the lower corners of the door, as indicated at 7 to accommodate the shanks of the trunnions 4. Also, the flanges of the lining panel 3 are notched at the lower corners of the door, as indicated at 7^a. The flanges of the outer and inner panels of the door have a telescopic relation, that is, the flanges of the lining member fit inside the flanges of the main panel. The notches, therefore, are complementary and afford passages for the shanks of the trunnions. The shank 4^a of each trunnion preferably comprises a base portion 4^b which extends through the notches at the corner of the door, and an arm 4^c rising from the portion 4^b and extending obliquely and terminating at the upper portion of the door. It will be noted that the main panel 2 of the door is so pressed as to provide a peripheral marginal shelf or bearing 8 adjacent the flanges of the member, the intermediate or main portion of the body of the sheet being pressed or dished outwardly so as to lie in a different plane. The portions 4^b of the shanks of the trunnions bear upon the shelf portion 8 at the lower portion of the door. At the upper ends of the arms 4^c are small extensions 4^d which bear upon the marginal bearing 8. The arms 4^c are also equipped near their upper ends with offset 105

lugs or feet 4^c which bear upon the depressed portion of the panel 2 at the points where the handle 5 is connected, the metal at these points being struck inwardly slightly, however, as indicated at 9. The outer panel 2 is secured to the portions 4^b and 4^c by stove bolts or screw bolts 10 which engage nuts 11. The upper bolts 10 pass through the base portions of the brackets 5^a of the handle, so that the same bolts which secure the upper ends of the arms 4^c to the main panel of the door serve also to secure the handle to the door. The main panel of the door is provided at its lower corners with perforations 12 through which the lower bolts 10 extend.

The shanks 4^a of the trunnions are provided with threaded or tapped perforations 13 which receive screws 14 which serve to 20 secure the lining panel 3 in position, so that the housing of the shanks of the trunnions is thus completed. As appears from Fig. 1, the portions 4^b of the shanks of the trunnions are provided with reenforcing ribs 4^f 25 which embrace the edges of the outer panel of the door.

When the door is in the open position shown in Fig. 3, the portions 4^b of the shanks of the trunnions rest upon the stops 30 1 with which the bearings B are provided. The bearings B are of a well known form, being open at their sides which are adjacent to the door, so as to receive the trunnions. One of the trunnions is equipped, as shown in Fig. 4, with a coil spring 15 which has one end secured to the trunnion and the other end engaging the bearing, so that the spring will tend to lift or counterbalance the door.

As appears from Fig. 2, the base portions 4^b of the shanks of the trunnions are separated from the lower flange 2^b of the main panel of the door by spaces 16; also, the lugs 4^d are separated from the upper flange 2^c by spaces 17. Thus, when the lining is applied, 45 the flanges of the lining are accommodated by these spaces.

From the description given, it will be understood that the door is carried wholly by the trunnions and their shanks, and that the shanks of the trunnions afford a very substantial reenforcement for the door. Moreover, the shanks of the trunnions are mainly housed in the space between the outer and inner panels of the door. Thus it is possible 55 to give to the door adequate strength and stanchness, while still employing comparatively light gauge metal for forming the panels. This is accomplished without marring the appearance of the door, since the 60 strong castings which are employed are well housed within the door. The outer panel of the door may thus be made an integral member, and may be suitably enameled, and its appearance will not be marred in any way. 65 The only exposed screws are the screws 10,

which may have nickel plated heads. The construction is strong, sanitary, and thoroughly adapted to its purpose.

The latch device 6 shown in Fig. 7 comprises a flat spring mounted on a ledge 6^a carried by the frame A and disposed inside the upper edge of the door, the spring being suitably shaped and extended through an opening 6^b in the frame. The outer end of the spring is curved into the form of a ring 6^c, the lower portion of which serves as a latch for the door. It will be understood from Fig. 7 that when the door is closed, the upper edge of the door will ride under the ring portion 6^c and the ring will snap over the upper edge of the door sufficiently to hold it in the closed position. The door may be released by lifting the spring through the medium of the ring-form handle.

In the modification shown in Fig. 8, A³ represents the outer panel of a door formed from sheet metal; and 4^g, 4^g represent trunnions. In this case, the trunnions are equipped with shanks 4^h which extend through notches 18 in the flanges at the lower corners of the door. In the illustration given, the shanks 4^h are formed integrally with each other. The shanks are secured to the panel by stove bolts 19. Such a construction is cheaper than the first described construction, but something is sacrificed in strength, owing to the omission of the arms which extend to the upper portion of the door and serve as a means for attachment of the handle.

In the modification shown in Figs. 9 and 10, A⁴ represents a door; A⁵ represents the frame of the range. The door comprises, as in the first described construction, an outer panel 20 and a lining panel 21. In this case, the trunnions or hinges 22 are of a different form. They have shanks 22^a which extend through notches with which the flanges of the door panels are provided at their lower corners. The shanks of the hinges are housed between the panels of the door and are secured to the panels by bolts 23 and screws 24. The hinges or trunnions 22 in this case are in the form of curved arms which extend through slots 25 with which the frame A⁵ is provided. The members 22 have connected with their inner ends links 26 whose upper ends are connected with the upper ends of the coil springs 27. The lower ends of the springs 27 are connected with the frame by screws or studs 28. This is a well known manner of counterbalancing a stove door, shown, for example, in Patent No. 1,444,153 granted February 6, 1923.

The foregoing detailed description has been given for clearness of understanding only, and no unnecessary limitations should be understood therefrom, but the appended claims should be construed as broadly as permissible in view of the prior art.

What we regard as new, and desire to secure by Letters Patent, is:

1. The combination with an oven frame provided with bearings, of a door comprising a sheet metal panel having an inturned marginal flange which is notched at its lower corners, and a pair of trunnions adapted to be supported in said bearings and having shanks extending through said notches and secured to said panel. 10
2. The combination with an oven frame provided with bearings, of a door comprising a main outer sheet metal panel and a lining panel spaced with relation thereto, and trunnions adapted to said bearings and having shanks housed between and carrying said panels. 15
3. The combination with an oven frame provided with bearings and with a shoulder 20 adapted to serve as a stop, and a door comprising an outer panel and an inner panel spaced apart, and trunnions adapted to said bearings and provided with shanks housed between said panels and serving to carry the same, at least one of said trunnions being equipped with a stop cooperating with said first named stop to support the door in open position. 25
4. The combination with an oven frame 30 provided with a door opening and with bearings adjacent the lower corners of the door opening, of a door comprising an outer main panel and a lining panel, said panels having telescopically related flanges with notches at the lower corners of the door, and trunnions engaging said bearings and provided with shanks which extend laterally inwardly through the notches and provided with extensions housed between and 35 serving as reenforcements for the panels. 40
5. A door comprising a main outer panel having an inturned marginal flange, a lining panel having an out-turned marginal flange telescopically received within said first named flange, said flanges being notched at the lower corners of the door, and trunnions having shanks extending through said notches and housed between said panels. 45
6. A door comprising an outer main panel 50 provided with inturned marginal flanges, a lining panel provided with out-turned marginal flanges received telescopically within said first named flanges, said flanges being provided at the lower corners of the door with notches, and trunnions provided with shank portions extending laterally through said notches into the space between said panels, screw bolts extending through the outer panel and attached to said shanks, and 55 screws connecting the inner panel with said shanks. 60
7. A door comprising an outer panel provided with inturned marginal flanges, a lining panel spaced with relation to said outer panel, said flanges being notched at the low- 65
- er corners of the door, and trunnions having shank portions extending through said notches and having arms extending therefrom to the upper portion of the door, means securing the outer panel to said shank portions and said arms, and means securing the inner panel to said shank portions and said arms. 70
8. A door comprising an outer main panel which is struck outwardly and provided with marginal inturned flanges and adjacent to said flanges with an internal peripheral bearing, said flanges being notched at the lower corners of the door, trunnions having shank portions extending through said notches and engaging said peripheral bearing, bolts securing said panel to said shank portions, and a lining panel covering the shank portions of said trunnions and secured thereto. 75
9. A door comprising a main outer panel having inturned marginal flanges notched at the lower corners of the door, the body portion of said panel being struck outwardly and provided with an inner marginal bearing adjacent said flanges, trunnions having shank portions extending through said notches and provided with arms extending to the upper portion of the door, said shank portions and said arms engaging said inner peripheral bearing and said arms being provided near their extremities with lugs engaging the inner surface of said panel adjacent said marginal bearing, bolts securing said lugs and said shank portions to said panel, and a lining panel enclosing said shank portions and arms. 80
10. A door comprising a main outer panel having inturned marginal flanges notched at the lower corners of the door, the body portion of said panel being struck outwardly and provided with an inner marginal bearing adjacent said flanges, trunnions having shank portions extending through said notches and provided with arms extending to the upper portion of the door, said shank portions and said arms engaging said inner peripheral bearing and said arms being provided near their extremities with lugs engaging the inner surface of said panel adjacent said marginal bearing, bolts securing said lugs and said shank portions to said panel, and a lining panel enclosing said shank portions and arms. 85
11. A door comprising a main outer panel having inturned marginal flanges notched at the lower corners of the door, the body portion of said panel being struck outwardly and provided with an inner marginal bearing adjacent said flanges, trunnions having shank portions extending through said notches and provided with arms extending to the upper portion of the door, said shank portions and said arms engaging said inner peripheral bearing and said arms being provided near their extremities with lugs engaging the inner surface of said panel adjacent said marginal bearing, bolts securing said lugs and said shank portions to said panel, and a lining panel having outturned marginal flanges notched at the lower corners and telescopically received within the flanges of said first named panel, and screws securing said lining panel in position. 90
12. A door comprising a main outer panel provided with an inturned marginal flange notched at the lower corners of the door, trunnions having shank portions extending through said notches and provided with extensions bearing against the inner surface of the door at the upper portion thereof, an external handle, bolts securing said handle 100
13. A door comprising a main outer panel having inturned marginal flanges notched at the lower corners of the door, the body portion of said panel being struck outwardly and provided with an inner marginal bearing adjacent said flanges, trunnions having shank portions extending through said notches and provided with arms extending to the upper portion of the door, said shank portions and said arms engaging said inner peripheral bearing and said arms being provided near their extremities with lugs engaging the inner surface of said panel adjacent said marginal bearing, bolts securing said lugs and said shank portions to said panel, and a lining panel enclosing said shank portions and arms. 105
14. A door comprising a main outer panel having inturned marginal flanges notched at the lower corners of the door, the body portion of said panel being struck outwardly and provided with an inner marginal bearing adjacent said flanges, trunnions having shank portions extending through said notches and provided with arms extending to the upper portion of the door, said shank portions and said arms engaging said inner peripheral bearing and said arms being provided near their extremities with lugs engaging the inner surface of said panel adjacent said marginal bearing, bolts securing said lugs and said shank portions to said panel, and a lining panel having outturned marginal flanges notched at the lower corners and telescopically received within the flanges of said first named panel, and screws securing said lining panel in position. 110
15. A door comprising a main outer panel provided with an inturned marginal flange notched at the lower corners of the door, trunnions having shank portions extending through said notches and provided with extensions bearing against the inner surface of the door at the upper portion thereof, an external handle, bolts securing said handle 115
16. A door comprising a main outer panel having inturned marginal flanges notched at the lower corners of the door, the body portion of said panel being struck outwardly and provided with an inner marginal bearing adjacent said flanges, trunnions having shank portions extending through said notches and provided with arms extending to the upper portion of the door, said shank portions and said arms engaging said inner peripheral bearing and said arms being provided near their extremities with lugs engaging the inner surface of said panel adjacent said marginal bearing, bolts securing said lugs and said shank portions to said panel, and a lining panel enclosing said shank portions and arms. 120
17. A door comprising a main outer panel provided with an inturned marginal flange notched at the lower corners of the door, trunnions having shank portions extending through said notches and provided with extensions bearing against the inner surface of the door at the upper portion thereof, an external handle, bolts securing said handle 125
18. A door comprising a main outer panel having inturned marginal flanges notched at the lower corners of the door, the body portion of said panel being struck outwardly and provided with an inner marginal bearing adjacent said flanges, trunnions having shank portions extending through said notches and provided with arms extending to the upper portion of the door, said shank portions and said arms engaging said inner peripheral bearing and said arms being provided near their extremities with lugs engaging the inner surface of said panel adjacent said marginal bearing, bolts securing said lugs and said shank portions to said panel, and a lining panel enclosing said shank portions and arms. 130

to said extensions, and a lining panel covering said shank portions and extensions.

12. A door comprising an outer main panel which is dished outwardly and provided with an inturned marginal flange and adjacent thereto with an internal marginal bearing, said flange being provided with notches, trunnions provided with shanks having base portions extending through said notches and engaging said marginal bearing and having extensions engaging the marginal bearing at the upper portion of the door, an external handle, bolts extending through the outer panel and connecting said handle with said extensions, bolts extending through the outer panel and connected with the base portions of said shanks, and a lining panel covering said shanks.

13. A door comprising an outer main panel which is dished outwardly and pro-

vided with an inturned marginal flange and adjacent thereto with an internal marginal bearing, said flange being provided with notches, trunnions provided with shanks having base portions extending through said notches and engaging said marginal bearing and having extensions engaging the marginal bearing at the upper portion of the door, an external handle, bolts extending through the outer panel and connecting said handle with said extensions, bolts extending through the outer panel and connected with the base portions of said shanks, a lining panel provided with an outturned marginal flange notched at its lower corners and telescopically received within said first named flange, and screws connecting said lining panel with said shanks.

GEORGE D. WILKINSON.
AUGUSTUS F. HARTER.
